UNITED STATES PATENT OFFICE.

JONATHAN L. JONES, OF ST. LOUIS, MISSOURI, ASSIGNOR TO HIMSELF AND
W. D. PORTER.

IMPROVED DEFENSIVE ARMOR FOR WATER AND LAND BATTERIES.

Specification forming part of Letters Patent No. 35,001, dated April 15, 1862.

To all whom it may concern.

It is known that I, JONATHAN L. JONES, of St. Louis, in the State of Missouri, have invented a new and useful Compound Casemate for War-Vessels and other War Structures; and I do hereby declare that the following is a full, clear, and exact description of the same, reference being had to the accompanying drawings, forming part of this specification, in which—

Figure 1 is a perspective view of a portion of a ship casemated according to my invention. Fig. 2 is an exterior view of the same. Fig. 3 is a horizontal section of the same. Fig. 4 is a perspective view of one of the plates of metal; Figs. 5 and 6, modifications of the improvement.

Similar letters of reference in the several figures indicate corresponding parts.

The nature of my invention consists in a novel manner of constructing and applying the plating to casemates of war-vessels and other war structures; also, in a novel manner of combining elastic cushions with this novel arrangement of plating and with the bolts which hold the parts of the casemate together.

To enable others skilled in the art to make and use my invention, I will proceed to describe the same with reference to the drawings.

A B are metal plates with narrow ribs $a a'$ $b b'$, extending at right angles out from one of their faces. These plates may be of any required thickness, and their ribs of such height and width as will impart great strength and rigidity to the plates. The length of the plates may be such as the structure to which they are applied may require. So, also, may the width of the plates be determined. Each plate has four ribs, one at each edge and two near the center. This number may be increased, if it is necessary, to give greater strength and rigidity to the plates. The ribs, if increased in number, must or ought to at least be disposed so as to operate as illustrated in the drawings. The angle-plates are all alike and can be produced on the same rolling-mill, and by their construction give a greater strength than any other plan used in constructing casemates, thus enabling me to reduce the weight of materials in a ship or boat of a given size and strength—a very im-

portant thing in constructing vessels to operate in shoal-water. They also assist in forming a continuous fastening between the inner and outer tiers of plating used in forming the casemate by means of their angles or ribs. They further, by their ribs, form chambers or channels to receive elastic cushions of rubber, cork, or other suitable material which is used between the plates for the purpose of saving the casemate from the injurious effects of sudden concussion of the ball and the plates. As the penetration of iron by cannon-balls involves the same mechanical principle of operation as the ordinary punching-machine, the ball performs the same office that the nipple of the punching-machine does. Therefore, as it is a well-known fact among mechanics that as long as the die of the machine remains rigid and unyielding, the nipple passes through the sheet of iron with apparent ease; but if some elastic substance is introduced between the bottom of the die, or the bed-plate of the machine allowed to spring, it is almost an impossibility to make the nipple of the punch penetrate the iron sheet. It follows that great advantage will be derived from any good and practicable mode of arresting the progress of a cannon-ball through the casemate of a ship or other war structure on the same principle. The use of an elastic cushion in the case of a punch causes the punch to glance off from the object with which it comes in contact, and the result must be the same if a similar cushion is used in a war structure when a ball strikes the plating of the casemate.

The angle-plates A B are applied to a casemate C by first applying an elastic cushion D to the outer surface of the casemate, and then setting the plain sides of the plates A against this cushion, the edges of the plates adjoining closely one another. Strips of rubber E or metallic springs or cork, or any other yielding substance, are now placed against the ribbed sides of the plates A, they being set snugly in the chambers or channels formed by the ribs $a a'$. A second tier of plates B are now set against the rubber cushions E, the edge ribs b of said plates entering between the central ribs a of the plates A, and the edge ribs a' of the plates A being inclosed by the central ribs b' of the plates B, thus

constituting break-joints on the inner and outer tiers of plates A B. The whole is now bolted through to the casemate structure by means of screw-bolts F, said bolts having heads on their outer ends and a nut on their inner ends, the nut being provided with an elastic washer c, in order that the strain on the bolt-heads shall be reduced, the elastic washers yielding to the rebound of the plates, and thus relieve the bolts from strain at their heads and save the heads from being torn off.

The plates, when firmly bolted to the casemate, have a space existing between their edge-angled parts and the bottom of the grooves formed by their intermediate angles, in order that a sufficient sliding movement of the surface-tier of plates may take place when a cannon-ball strikes them to allow the rubber cushions to come into effective play. Were not this provision made, the cushion would serve no effective purpose unless the surface-plates were cupped or depressed injuriously by the cannon-ball. Now, it is a very important thing if a continuous surface can be so applied to a casemate that every component part of that surface has a chance to follow any one part that is deflected or thrown out of its normal position by the force of a cannon-ball. My arrangement accomplishes this end, as provision is made for all the plates on the surface to approximate to the foundation-plates; and it goes farther by allowing the plates on the surface to recede connectedly from the foundation-plates and to draw without strain the through-bolts along with them a sufficient distance to relieve the bolt-heads and save them from being stripped off.

By my improvements it will be seen that a continuous double metal wall to the casemate is formed. This is important, experience proving that the wider the sheets are the greater the resistance to buckling or "cupping" when a cannon-ball strikes the sheet. Again, that two surfaces are much more difficult to penetrate or break than one, and that the first one-sixteenth of the outer fibers of wrought-iron has more tenacity than the next one-fourth inch. Consequently two sheets separated have more strength than one of a thickness equal to the two thinner sheets. Again, that the weakest point in the present mode of constructing iron sheets for casemates are at the joints or laps, and if they are prevented from giving way at that point the iron offers greater resistance to the percussive action of a cannon-ball; hence it is obvious that the continuous sheet with ribs and without laps is much more durable than the common lap or grooved sheets. Again, that it is much harder to bend a thin plate with ribs such as I show than it is to bend a plate of double the thickness that has no flanges or ribs, from the fact that the flanges or ribs have to bend in an opposite direction from the fibers, this being the plan on which the plates A B are rolled.

My invention will, I believe, render the casemates of vessels, fortifications, and other war structures proof against cannon-balls with less material than any other plan that has been used or proposed.

In Fig. 5 a modification of my invention is shown. This plan embraces the angle-plates; but at the edges of the outer tier of plates an angle lap-joint is formed. This was my first idea, and its adoption I would have recommended had it not required two different machines to roll out the plates and experiments shown that lap-joints are objectionable, for the reason that when a cannon-ball strikes plating with lap-joints it forces the inner edge into the wood and causes the plates to bend or buckle up.

My invention might be applied with advantage in the construction of "iron-clad" steamers or vessels. The angle plates, of course, must in that case be rolled to conform to the different parts of the ship.

I do not claim angled plates irrespective of construction and mode of application; nor do I claim a single tier of angled plates bolted to knees of a ship or other structure; nor do I claim two or more tiers of flat plates separated by angle knees or struts and held in place by rivets at their adjoining edges; nor do I claim angled plates or ribs for forming channels to receive plain or flat foundation and surface plates; nor do I claim elastic packing-cushions interposed between two tiers of immovable plates; but

What I do claim as my invention, and desire to secure by Letters Patent, is—

1. Metallic plates as the defensive armor of ships and land-batteries when the plates have a flange at the edges and have intermediate flanges, and when the plates are applied in two or more tiers or thicknesses, so as to form recesses between them, and also when the plates otherwise are constructed and applied substantially as and for the purposes set forth.

2. The combination of armor-plates which have a flange at each edge and intermediate flanges, and are applied, as described, with divided elastic cushions, substantially in the manner and for the purpose set forth.

3. The combination of two or more tiers of angle-plates, constructed and applied as described, with intermediate cushions E and foundation-cushions D, substantially in the manner and for the purpose set forth.

4. The combination of elastic washer-cushions c, bolts F, angle-plates A B, constructed and applied as described, cushions E, and casemate or side of a vessel, substantially as and for the purpose described.

JONATHAN L. JONES.
